Patented Mar. 8, 1966

204,001

PUTTER HEAD

Sylvan M. Lubin, 1821 Navaho Circle,
Palm Springs, Calif.

Filed Mar. 29, 1965, Ser. No. 84,503

Term of patent 3½ years

(Cl. D34—5)

FIG. 1.

FIG. 2.

FIG. 3.

FIG. 4.

FIG. 5.

The broken lines indicating a shaft are for purposes of illustration only.

I claim:

The ornamental design for a putter head, substantially as shown and described.

No references cited.
